INTERDENTAL STIMULATOR

Joseph C. Muhler, Indianapolis, Ind., assignor to
Plastek Company, Sturgis, Mich.

Filed Mar. 14, 1969, Ser. No. 16,250

Term of patent 14 years

Int. Cl. D24—03; D28—01
U.S. Cl. D24—1

FIG. 1 is a perspective view of an interdental stimulator showing my new design;

FIG. 2 is a front elevational view thereof;

FIG. 3 is a top plan view thereof;

FIG. 4 is a bottom view thereof;

FIG. 5 is a left-end view thereof; and

FIG. 6 is a right-end view thereof.

I claim:

The ornamental design for an interdental stimulator, as shown.
